UNITED STATES PATENT OFFICE.

FRANK J. QUIGAN, OF BROOKLYN, NEW YORK, ASSIGNOR TO SIMON ZINN INC., A CORPORATION OF NEW YORK.

CLASP FOR HAND-BAGS.

1,241,657.

Specification of Letters Patent.

Patented Oct. 2, 1917.

Application filed February 9, 1917. Serial No. 147,535.

To all whom it may concern:

Be it known that I, FRANK J. QUIGAN, a citizen of the United States, residing at 1023 East 2nd street, Brooklyn, county of 5 Kings, New York, have invented certain new and useful Improvements in Clasps for Hand-Bags, of which the following, taken in connection with the accompanying sheet of drawings, is a full, clear, and concise 10 description thereof.

This invention relates to a clasp for hand bags, and more particularly to a locking means for preventing the accidental opening of the bag.

15 It has for its object the provision of a clasp locking means characterized by simplicity of construction and efficiency of operation.

Other objects of the invention will manifest 20 themselves upon a reading of the following description.

While this invention has been set forth in a certain preferred embodiment, it will be understood that modifications may be 25 made without departing from the spirit and scope thereof.

Like reference characters refer to like parts throughout the several figures.

The invention is illustrated in the accompanying drawing, in which,—

30 Figure 1 is a perspective, partly in section, of a hand bag provided with my improved form of locking means;

Fig. 2 is a plan view, with parts broken 35 away, showing the locking means conditioned to function;

Fig. 3 is a section taken on line III—III of Fig. 1;

Fig. 4 is a view in section with parts 40 broken away showing the position of the resilient engaging member when not functioning;

Fig. 5 is a view, similar to Fig. 4, showing the locking member engaging its keeper.

45 In the hand bag shown in the drawing, the numeral 1 designates the body of a hand bag provided with a frame 2, having sections or hinged members, 3 and 4. Each of the hinged members is U-shaped in cross 50 section, and is likewise U-shaped in general conformation terminating in end extensions adapted to be pivoted together. The frame members 3 and 4 are secured to the

body of the bag in any suitable manner, such as gluing, riveting, etc. The member 3 is provided with means suitable to accommodate a strap or carrying member 5. Located at a convenient point, preferably near the center, is a clasp or knob 6, which is so mounted as to be capable of being displaced or tilted backwardly so as to permit the disengagement or opening of the frame members 3 and 4. The mounting of the knob forms no part of my invention, and may be accomplished in any suitable manner, such as shown in Fig. 3, comprising a resilient member 7 mounted between the side walls of the frame member 3, and projecting through an aperture in the base thereof. This projection is extended far enough to provide a body portion 8, having a U shape, with the end of the short leg thereof secured to the base or edge of the knob 6 at a point diametrically opposite to the aperture in the frame member 3. The center of the body portion 8 is provided with an aperture suitable to accommodate a downwardly projecting stud 9, extending axially from the head of the knob 6. A bur 10 is formed upon the upper surface of the frame member 4, the former being positioned to engage the secured end portion of the flexible member 7. The flexible or resilient member 7 may be mounted in the frame member 3 by any suitable means, which would readily suggest itself to those skilled in the art, such as by a pivot, or like means. The locking means comprises a resilient latching member 12, having one of its ends secured to the base portion of the frame member 4. This may be effected in any desired manner, such as by soldering, swaging, and the like. The secured portion of the member 12 is given a wave-like or corrugated formation for the purpose of reinforcing its mounting and resiliency. The free end of the member 12 is bent slightly downward, and the member is given a downward tension. Positioned beneath the resilient member 12 are apertures 13 adapted to receive projecting members 14 and 15, carried by the frame member 3. The projecting member 15 is provided with a notch in its upper surface suitable to accommodate the free end of the resilient member 12. This 105 projecting member 15 with its notched por-

tion functions as a keeper for the free end of the latching member 12 when these parts are permitted to engage.

The latching member 12 is functioned by 5 a rotatably mounted member 16, the member 16 being journaled in the side walls of the frame member 4, and comprises an exterior head portion 17 with a reduced portion 18, the latter having a portion of its surface 10 removed so as to form a seat for the intermediate portion of the latching member 12. The exterior portion 17 of the member 16 is provided with an aperture into which is fitted a gripping or operating member 19. 15 This operating member may be of any convenient design or shape, its chief function being to furnish a means for rotating the member 16, and also to facilitate the opening of the hand bag when the knob 9 is bent 20 backward. It will be noted that forming the recess in the reduced portion 18 of the member 16 results in making a cam surface for the operation of the resilient member 12. When it is desired to lock the frame members 3 and 4 together, all that is necessary is 25 to bring the recess in the member 18 into engagement with the resilient member 12. This will permit a downward movement of the free end of said member, due to its inherent downward tension, so that the end of 30 the member 12 comes into engagement with the slot formed in the member 15. While in this position it is obvious that the frame members 3 and 4 cannot be separated, or, 35 in other words, these members are firmly locked together, preventing accidental opening thereof.

When it is desired to unlock the hand bag, all that is required is to turn the operating 40 member 19 through an angle sufficient to effect the disengagement of the latching member 12 from the recess in the reduced portion 18. As this movement takes effect the free end of the member 12 is gradually 45 raised until it clears the aperture in the projecting member 15, thus allowing the frame members, 3 and 4, to be opened upon the manipulation of the knob 6. The angle of rotation of the operating member 19, al- 50 though not necessarily, is preferably made 180°, so that the member 19 will lie thereon and come into close contact with the body of the bag, thus being less likely to catch on other objects. As a matter of convenience 55 one side of the operating member 19 may be given a designation such as "open" or "close," which will assist the owner of the bag in being able to determine at a glance whether it is in locked or opened condition.

60 While I have herein shown and particularly described the preferred embodiment of my invention, I do not wish to be limited

to the precise details of construction, as changes may readily be made without departing from the spirit and scope thereof. 65

What is claimed is:

1. A clasp for hand bags, comprising a pair of pivoted members having a U-shaped cross section, a resilient latching member mounted within the U-shaped portion of one of said members, a lateral projection carried upon the other of said members and provided with a recess for the accommodation of said resilient member, and means for effecting the engagement or disengagement of 70 said resilient member with said recess, said means including a rotatably mounted member having a cam surface and an operating member for actuating said rotating member. 75

2. A clasp for hand bags, comprising a pair of pivoted frame members having a U-shaped cross section, a resilient latching member mounted within the U-shaped portion of one of said members, an aperture in one of the side walls of said member, said aperture being formed beneath the normal position of said resilient member, a projection carried upon the other of said members and adapted to enter said aperture, said projection being provided with a recess for the 80 accommodation of said resilient member, and means for effecting the engagement or disengagement of said resilient member with said recess, said means including a rotatably mounted member having a cam surface, and an operating member for actuating said 85 rotatable member. 90

3. A clasp for hand bags comprising a pair of pivoted frame members having a U-shaped cross section, a resilient latching member concealed within one of said frame members and having one of its ends secured to the base of the U-shaped portion, the free end of said resilient member having a tension in a direction away from its support, 100 an aperture in one of the side walls of said frame member, said aperture being formed beneath the normal position of the free end of said resilient member, a projection carried upon the other of said frame members 105 and adapted to enter said aperture, said projection being provided with a recess for the accommodation of said resilient member, and means for effecting the engagement or disengagement of said resilient member with said recess, said means including a rotatably mounted member having an active 110 and an inactive surface adapted to engage said resilient member, whereby said resilient member is rendered effective when said inactive surface is functioning and ineffective 115 when said active surface is functioning. 120
